UNITED STATES PATENT OFFICE.

GEORGE ROBERT HOAGLAND, OF EASTON, PENNSYLVANIA.

NON-REFILLABLE BOTTLE.

1,179,006.

Specification of Letters Patent. Patented Apr. 11, 1916.

Application filed May 28, 1915. Serial No. 31,003.

To all whom it may concern:

Be it known that I, GEORGE R. HOAGLAND, a citizen of the United States, residing at Easton, in the county of Northampton and 5 State of Pennsylvania, have invented a new and useful Non-Refillable Bottle, of which the following is a specification.

The device forming the subject matter of this application is a non-refillable bottle, and 10 the invention aims, primarily, to improve the construction of the cage which is located in the neck of the receptacle above the valve therein.

It is one object of the invention to provide 15 novel means for supporting in the cage, a baffle which is located below an opening in the top of the cage.

It is within the province of the disclosure 20 to improve generally and to enhance the utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made without 30 in the scope of what is claimed, without departing from the spirit of the invention.

In the accompanying drawing:—Figure 1 shows in fragmental longitudinal section, a bottle wherewith the device forming the subject matter of this application has been assembled; Fig. 2 is a side elevation of the cage detached from the bottle; Fig. 3 is a cross section on the line 3—3 of Fig. 2; Fig. 4 is a cross section on the line 4—4 of Fig. 2.

In carrying out the present invention 40 there is provided a receptacle 1, the neck of which is denoted by the reference character 2. At the point where the neck 2 merges into the body portion of the receptacle, a 45 tapered seat 3 is formed. Coöperating with the seat 3 is a frusto-conical valve 4. Intermediate its ends, the neck 2 of the receptacle 1 is equipped with an internal, circumscribing 50 groove 5.

Located within the neck 2 of the receptacle 1 is a cage which preferably is fashioned from metal throughout, the cage comprising a top 6 having an opening 7 and resilient arms 8 depending from the top. Intermediate 55 their ends, the arms 8 are bent outwardly to form loop-shaped projections 9 adapted

to be received in the groove 5 to prevent the cage from moving longitudinally of the neck 2 of the receptacle. The inner ends of the arms 8 are bent toward the axis of the receptacle to form slidably overlapped feet 10. These feet, when the cage is mounted in the receptacle as shown in Fig. 1, constitute a stop for the valve 4 as will be evident from Fig. 1. The arms 8 are cut away on both 60 edges as shown at 11, the material thus freed being turned toward the axis of the receptacle to form projections 12. The notches 11 coöperate to form in each arm, a reduced neck 15. The invention comprises 65 a baffle 16 in the form of a plate having notches 17 in its edge. Certain of the notches 17 receive the reduced necks 15 of the arms 8, the baffle 16 lying beneath the opening 7 in the top 6 of the cage and being 70 disposed between the upper and lower projections 12.

When the receptacle 1 is in an upright position as shown in Fig. 1, the valve 4 is 75 lodged in the seat 3 and liquid cannot be 80 poured into the receptacle. When the receptacle is in an inclined position, the valve 4 slides out of the seat and abuts against the feet 10 of the cage. Then the contents of the receptacle 1 flow through the notches 85 17 in the baffle 16 and passes outwardly through the opening 7 in the top 6 of the cage. Owing to the presence of the baffle 16, access cannot be had to the valve 4 through 90 the opening 7.

In assembling the cage with the receptacle, the baffle 16 is mounted in place between the arms 8 and the projections 12 are bent in to hold the baffle. Then, the cage is pushed into the neck 2 of the receptacle 1, 95 the arms 8 springing toward each other and the feet 10 sliding on each other. When the projecting loops 9 are opposite the groove 5, the arms will expand, and the loops will be engaged in the groove 5. Thus the cage is 100 assembled with the neck 2 of the receptacle.

Having thus described the invention, what is claimed is:—

1. In a device of the class described, a receptacle having a seat and provided with a circumferential groove; a valve coöperating with the seat; a cage comprising a top having an opening, and arms depending from the top, the inner ends of the arms being extended toward the axis of the receptacle 105 to form slidably overlapped feet, the arms intermediate their ends being outwardly ex- 110

tended to form projections engaged in the groove; a baffle within the contour of the arms and below the opening, the baffle being provided with notches, and the arms being 5 cut away to define reduced necks fitting in the notches, the material freed by the cutting away of the arms being inturned to form baffle holding projections.

2. In a device of the class described, a 10 receptacle; a cage in the receptacle, the cage comprising resilient arms, the arms and the receptacle being provided with interengaging elements preventing a movement of the cage longitudinally of the receptacle; a 15 baffle within the contour of the arms and provided with notches, the arms being cut away to define reduced necks fitting in the notches, the material freed by the cutting away of the arms being inturned to form 20 baffle holding projections; and a valve operating in the receptacle below the cage.

3. In a device of the class described, a receptacle; a cage in the receptacle, the cage comprising resilient arms, the arms and the

receptacle being provided with interengaging elements preventing a movement of the cage longitudinally of the receptacle; a baffle within the contour of the arms and provided with notches, the arms being cut away to define reduced necks fitting in the 30 notches; and a valve operating in the receptacle below the cage.

4. In a device of the class described, a cage comprising a top having an opening, and resilient arms depending from the top; 35 a receptacle receiving the cage, the receptacle and the arms having interengaging elements which coact to prevent the cage from moving endwise in the receptacle; and a removable baffle held by and between the 40 arms, and independent of the top, the baffle engaging the arms intermediate their ends to act as a fulcrum for the arms, thereby to stiffen the arms.

In testimony that I claim the foregoing 45 as my own, I have hereto affixed my signature.

GEORGE ROBERT HOAGLAND.
